ELECTRICALLY HEATED CUSHION

Hanns Kindermann and Grete Kindermann, née
Huesmann, Radlitz, Post Steinau, GermanyApplication March 29, 1934, Serial No. 718,033
In Germany April 1, 1933

3 Claims. (Cl. 219—46)

This invention relates to improvements in electrically heated cushions of the usual type consisting of heating wires, a fabric to which the heating wires are secured (heating wire carrier) and 5 one or more protecting covers. The object of the invention is to make the cushion fireproof in all operating conditions.

It is already known to cover the heating wires or spirals with thick or thin single or multiple 10 asbestos threads. This covering is not sufficient to prevent short circuit sparks and burning of the cushion as, for example, when the heating wire is broken and the wire ends come into contact through the asbestos covering. The heating 15 wire carrier consisting of fabric similar to a dish-cloth on which or in which the asbestos covered wires are inserted is ignited by the sparks or by the heating of the wires and then smoulders like tinder.

20 This danger of fire in the known heated cushions is effectively prevented by the present invention by the fabric carrying the heater wires, which itself is inflammable, being made fireproof by impregnation by suitable means. The 25 impregnation of a fabric for the present purpose can be effected by various means such as waterglass molasses with calcium or ammonium borate and a small addition of acid, sodium molybdate or the like. Experience has, however, 30 shown that while the known impregnating means prevent burning with flames, smouldering of the fabric may still take place under certain circumstances. This is of especial importance in a heated cushion because the fabric forming 35 the heating wire carrier in a heated cushion is surrounded by further protective coverings usually a bag of flannel and a further bag of linen. When the heater wire carrier smoulders it is possible for the surrounding fabric to become 40 ignited and to burn.

45 Some of the known impregnating means have the further disadvantage that at the comparatively high temperatures of 80° C. and more, which occur in such a heated cushion, the action of the heat on the impregnating means causes the production of unhealthy vapours and after a time the impregnating agent evaporates or an 50 unpleasant smell is produced which is found very detrimental in the use of the cushion.

55 These disadvantages are avoided according to the invention by the fabric acting as heating wire carrier being impregnated with a special solution which consists essentially of ammonium sulphate, ammonium chloride, boric acid and borax dissolved in water, to which is preferably

added small quantities of a condensation product of urea and formaldehyde, for example, the preparation known by the name lukron.

According to the invention also the heating wires, the temperature regulator and so forth, are 5 covered by the impregnated fabric in such a manner that flames produced by short circuit and the like, even after a long time, are not able to set fire to the outer coverings.

The invention is illustrated by way of example 10 in the accompanying drawing in which

Fig. 1 shows an electrically heated cushion according to the invention partly opened.

Fig. 2 shows a detail of the heated cushion in another constructional form.

Fig. 3 shows a further constructional form of the cushion according to the invention and

Fig. 4 shows a detail of the cushion.

In the drawing 1 are the heater wires of the cushion which as usual consist of an asbestos 20 core on which the heating wire is wound helically. For the purpose of insulation the heating wire is covered in the known manner with asbestos, the heating wires 1 are arranged on or in an impregnated fabric 2 which itself is enclosed 25 by a flannel bag 3 which in general is further protected by a linen bag 4.

According to the invention the fabric 2 covering the heating wire 1 is fireproof with a suitable means and preferably impregnated with a 30 liquid which consists essentially of a solution of ammonium sulphate, ammonium chloride, boric acid and borax. A particularly favourable result is obtained with a liquid consisting of 5-10 parts by weight of ammonium sulphate, 1-4 parts 35 ammonium chloride, 2-5 parts boric acid and 1-3 parts of borax dissolved in water in the proportion of 1-2 to 1-4. The concentration of the salt solution depends on the thickness and kind of fabric. It is advisable to add to this salt solution small quantities of condensation product of 40 urea and formaldehyde, known in commerce as lukron, for example, in the proportion of 1-20 and 1-25. With this impregnating liquid according to the invention, the fabric becomes fireproof so that even with an open flame the fabric 45 will not smoulder or char. Even when the heating wires are greatly overloaded, no vapours are produced which are unhealthy or unpleasant to the user of the cushion.

50 The impregnation with the said liquid has not only the advantage that cheap fabric, for example a kind of dish-cloth, can be used for the part 2 acting as heater wire carrier but also the advantage that this salt solution is very cheap. 55

The action of this salt solution is further increased according to the invention by roughening the fabric as then it soaks up the solution very well.

5 In order to avoid any danger of fire according to the invention the following construction of the heating cushion is used.

The innermost fabric 2 acting as heating wire carrier consists of one piece and forms two folded parts 5 and 6 laid one above the other. The asbestos covered heating wires 1 are placed on the one part 5 and are held by a thin impregnated muslin fabric 6 which is fastened to the part 5 of the fabric by quilting indicated at 7. Further, 10 according to the invention, tongues 8 and 9 secured to the part 5 by means of quilted screens and also made of impregnated fabric are provided which serve for covering the temperature regulator 10 arranged in the heated cushion, or 15 for covering the connecting points 11 between the lead-in cable 12 and the heater wires 1. As at these points, on account of poor contact or fracture of the cable or heater wires, short circuits and ignition thereby may occur, this covering of 20 the danger points is ineffective protection against fire. Preferably, the tongues according to Fig. 2 are so constructed that they cover the parts to be protected on both sides, that is, according to Fig. 2 the connecting points 11 are covered by the 25 parts 13 and 14 of the tongue 9.

A further constructional form of the heated cushion according to the invention is illustrated according to Fig. 3. Here a bag 15, which is non-inflammable on account of impregnation, is placed over a heater wire carrier 16. In this case the part 16 may consist of combustible material because the bag 15 completely encloses any parts that may catch fire. This result is obtained in 30

a similar way that the fabric 2 of Fig. 1 by the parts 5 and 6 being stitched together round the edges have the insertion of the heating wires.

According to the invention also the connecting points in the heated cushion, for example 11, 5 are covered with fireproof pieces or tubes of fabric. At branch points, as, for example, at 17, the pieces of fabric are made hose-like and consist according to Fig. 4 of two small tubes 18 drawn over the heating wire 1. Over the adjoining ends of which or the connecting point 19 a further fireproof fabric tube 20 is drawn. 10

The above described impregnation according to the invention is not illustrated to heated cushions but can of course be used with the same result 15 in heated covers, mats, aviators' clothing, firemen's clothing and so forth.

What we claim is:

1. An electrically heated cushion including a heating wire carrier of combustible fabric impregnated with a solution containing ammonium sulphate, ammonium chloride, boric acid and borax and a plurality of protecting covers. 20

2. An electrically heated cushion including a heater wire carrier of combustible fabric impregnated with a liquid containing 5-10 parts by weight ammonium sulphate 1-4 parts ammonium chloride, 2-5 parts boric acid, 1-3 parts borax dissolved in water in the proportion of 1-2 to 1-4 and 25 a plurality of protecting covers. 30

3. An electrically heated cushion including a heating wire carrier of combustible fabric impregnated with a salt solution containing ammonium sulphate, ammonium chloride, boric acid and borax with a small addition of condensation product of urea and formaldehyde. 35

HANNS KINDERMANN.
